Mark V. Drury

UNITED STATES PATENT OFFICE.

WALTHER GLOOR, OF NEW YORK, N. Y.

PROPELLER-SHAFT.

1,396,325.

Specification of Letters Patent.

Patented Nov. 8, 1921.

Application filed March 2, 1921. Serial No. 449,175.

To all whom it may concern:

Be it known that I, WALTHER GLOOR, citizen of Switzerland, residing at New York, in the county of New York and State of New York, have invented certain new and useful Improvements in Propeller-Shafts, of which the following is a specification.

The present invention relates to screw propellers in which the blades are reversible relative to the longitudinal axis of the propeller shaft, so that the direction of propulsion can be reversed without reversing the rotation of the propeller shaft.

The object of this invention is to provide a reversing or feathering mechanism which will be simple in construction, and effective in operation.

A further object of my invention is to so construct and mount the blades as to enable them to retain their adjusted position while in operation.

A still further object of this invention is to provide means whereby the reversing operation of the blades will be greatly facilitated.

With the aforesigned and other objects in view, my invention consists substantially in the novel construction and arrangement of parts hereinafter more fully described and defined in the appended claims.

In the accompanying drawing in which similar reference characters denote corresponding parts, Figure 1 is a side elevation of the stern part of the boat equipped with my new propeller; Fig. 2 is a face elevation of the lever mechanism for operating the blades; Fig. 3 is a vertical section on line 3—3 of Fig. 2; Fig. 4 is an end view of the propeller hub showing the slides engaging the blades; Fig. 5 is a section on line 5—5 of Fig. 4; Fig. 6 is a section on line 6—6 of Fig. 4; Figs. 7 and 8 are perspective views of the ends of the interposed members engaging the blades; Fig. 9 is a side elevation of a propeller blade, and Fig. 10 an elevation thereof at a right angle to that of Fig. 9.

Referring to the drawing, 10 denotes the main power propeller shaft adapted to be driven continuously in one direction and which toward the rear is made hollow and tapering or conical as at 10', said hollow tapering portion projecting outwardly through the hull of the vessel 11. Fixed to the outer

end of said hollow part of the propeller shaft is a hollow boss or hub 12 which according to the present embodiment is composed of three circumferential sections, a conical section 13, two intermediate externally cylindrical sections 14 and 15, and a conical cap 16. The conical section 13 is formed with a central conical bore to engage the tapered hollow part 10' of the propeller shaft, and at its rear end has a reduced cylindrical projection 13' to screw into a threaded cylindrical hollow 14' of the adjacent section 14. The projection 13' is hollow as at 13' to accommodate a nut 17 working on the threaded portion 10' of the propeller shaft 10, and whereby the section 13 is tightened on the latter. The other intermediate section 15 is provided with a threaded projection 15' to engage the screw threaded mouth 16' of the cap 16. The threaded engagement of the different sections with one another must be contrary to the direction of rotation of the propeller shaft.

The intermediate sections 14 and 15 are provided with central sockets 14' and 15' respectively, arranged in axial alinement with each other and substantially of polygonal form with as many sides as there are blades. In the example shown, the propeller comprises three blades 18 and accordingly the sockets 14' and 15' are in form of equilateral triangles. The two sections 14 and 15 are adapted to bear with their opposite plane surfaces on each other in a plane perpendicular to the central axis of the main propeller shaft, and to be joined together by bolts 15' or the like as shown in Figs. 4, 5, 6. In the bearing surfaces each intermediate section is formed with radially extending cylindrical holes 19 each hole being formed with a plurality of annular ribs 19'. Each propeller blade 18 is constructed so that relative to the central longitudinal axis one of its sides is considerably wider than the other, and the wider side terminates in a comparatively sharp edge 18'. Each propeller blade 18 is formed at its inner end with a cylindrical stem 20, correspondingly grooved as at 20' so as to properly fit into the ribbed sockets 19 of the sections 14 and 15. The sides of each propeller blade adjacent to the circumference of the hub sections 14, 15 are extended in the direction of

the stem 20 so as to provide a pair of shoulders 18², 18³ which are adapted to bear against the cylindrical surfaces of the sections 14, 15 of the hub. This construction 5 affords the desired amount of free rotation of the blades around the longitudinal axes of their stems 20, and prevents displacement in radial direction relative to the propeller shaft. The wider side of each blade 10 which carries the cutting or advancing edge 18' receives a greater amount of reaction from the water than the other side, such reaction tending to automatically hold the shoulders 18² and 18³ steady against the circumference of the sections 14 and 15. The 15 main support for each blade is the stem 20 which is snugly held in the bearing and a tendency of the blades to rotate farther in their sockets 19, because of the greater 20 amount of pressure on the wider cutting side of the blades is resisted by the contact of the shoulders 18² and 18³ against the sections 14 and 15.

Extending through the hollow portion 10' 25 of the main propeller shaft 10 are members arranged concentric to and adapted to revolve with said propeller shaft. In the present example, these members are made in form of a sleeve 21 and a rod 22 borne in 30 the hollow part 10' of the propeller shaft and within one another. These members 21, 22 are movable in opposite direction relative to one another and longitudinally of the propeller shaft 10. The rear ends 21', 35 22' of the sleeves 21 and rod 22 project into the polygonal sockets 14² and 15² and are each formed with a plurality of wing shaped members 23, 24 respectively, each of triangular prismatic form to fit the triangular sockets 14² and 15² and bear on the 40 sides thereof. The two sets of wings are so disposed relative to one another as to slidably engage with one another or interlock as shown in Fig. 4. The outer face of each 45 wing 23 is provided with a recess 24' extending transversely relative to the axis of the propeller shaft (Figs. 7 and 8). Slidably fitted in each recess or groove 24' is a slide 50 25 provided with a substantially cylindrical hole 26. These holes 26 constitute sockets for the engagement of pins 27 projecting eccentrically from the inner end of the stem 20 of each propeller blade. Each blade has two eccentric parallel pins 27 adapted to 55 engage the hole 26 of two adjacent slides 25 removable in the groove 24' of the different sets of wings 23, 24. The axes of the pins 27 are located in the general plane of the corresponding blade 18. Now it is obvious that by the longitudinal opposite movement 60 of the members 21, 22 the slides 25 borne within the grooves or recesses of the corresponding wings 23, 24 thereof will move transversely to the latter and the 65 blades rotatively borne in the sockets of the

hub, and engaging the slides 25 of the two sets with their crank pins 27 will be turned around their longitudinal axes reversing their position. In other words, the longitudinal movement of the members 21, 22 70 will cause the axes of the pins 27 to swing in circles at different distances from the radial planes of contact between the several parts of the wings.

Any suitable means may be provided for 75 shifting the members 21, 22 in opposite direction, either simultaneously or otherwise.

In the present example I provide a lever 28 which is fulcrumed at 29 to a stationary part and which is connected through a 80 toggle joint 30 to the upper ends of two yokes 31 and 32. The opposite ends of the yokes are fulcrumed at 31', 32' to a stationary part 33 (Figs. 2 and 3). The yoke 31 carries a collar 34 in which revolubly 85 bear the spokes 35' of a disk 35 fixed to the front end of the member or rod 22. The yoke 32 likewise carries a split collar 36 in which are revolubly borne the spokes 37' of a disk 37 fixed to the front end of the sleeve 21. 90 The propeller shaft is recessed as at 10³ for the passage of the spokes 35' and 37' and hollow at 10⁴ to accommodate the disks 35, 37.

The manipulation of the reversing device 95 is as follows:—

When the lever 28 is depressed, the toggle links 30 will be separated causing the yokes 34, 35 to swing in opposite directions, and thereby shift the members 22, 21 longitudinally. As a result thereof, the wings 23, 24 will be displaced relative to one another in opposite directions, and the propeller blades 18 will be swung around their longitudinal axes by virtue of the circular motion imparted to the pins 27 by the slides 25. During this reversal of the position of the propeller blades, the shoulders 18², 18³ will bear snugly against the cylindrical surface of the hub sections 14, 15 of the hub 12. 110

By moving the lever 28 upwardly the toggle links 30 will be drawn together, as a consequence of which the yokes 34, 36 will be returned into their initial position, restoring the blades 18 to their original position. 115

When the power of the motor is shut off while the boat is moving forward, the water will be caused to drag backward upon the cutting edges of the blades, and thereby assist the operator in effecting the reversal of the position of the blades by the means heretofore described. When the boat is moved backward as soon as the power of the motor is turned off, the water will help to 120 swing the blades around the axis of the hubs toward the forward driving position.

While I have described one embodiment of my invention, I do not wish to restrict myself to the details of the construction, 130

since various embodiments may be made therein, without departing from the principle of my invention.

What I claim and desire to secure by 5 Letters Patent is:—

1. In a screw propeller, the combination with a propeller shaft of independent members movable longitudinally of and revolving with said shaft, a propeller hub secured 10 to said propeller shaft, slides in said members and propeller blades borne in said hub and adapted to engage said slides, so that by the displacement of said members, said blades will be turned on their longitudinal 15 axes to reverse the direction of propulsion. 70
2. In a screw propeller, the combination with a propeller shaft, of independently and longitudinally movable members extending through and revolving with said propeller 20 shaft, a propeller hub fixed to said propeller shaft, the ends of said members projecting into and guided in said hub, slides freely movable in said ends and propeller blades 25 rotatively borne in said hub and engaging said slides so that by the displacement of said members, said blades will be turned around their longitudinal axes to reverse the direction of propulsion. 75
3. In a screw propeller, the combination 30 with a propeller shaft of two independently and longitudinally movable members extending through and revolving with said shaft, a propeller hub fixed to said propeller shaft, the ends of said members projecting 35 into and guided in said hub, slides freely movable in said ends, propeller blades revolubly borne in said hub and having eccentric projections adapted to engage the slides movably in two adjoining ends of said 40 members, so that by the longitudinal displacement of the latter, the said blades will be turned on their longitudinal axes to reverse the direction of propulsion. 80
4. In a screw propeller, the combination 45 with a propeller shaft, of two independently and longitudinally movable members arranged concentric to and revolving with said shaft, a propeller hub fixed on said propeller shaft and formed with a polygonal central 50 socket, the ends of said members projecting into said socket and being formed each with a plurality of prismatic guides slidably bearing in said socket, the guides of one member being adapted to interlock with 55 those of the other, freely movable slides in said guides and propeller blades revolubly borne in said hub and each being adapted to engage the slides of adjoining guides of said two members, so that by the longitudinal 60 displacement of the latter, the said blades will be turned on their longitudinal axes to reverse the direction of propulsion. 85
5. In a screw propeller, the combination 65 with a propeller shaft, of a hub fixed to said shaft, two sets of inter-engaging members 90 guided in said hub and movable in opposite directions relative to one another and longitudinally of said propeller shaft, propeller blades rotatively borne in said hub and each engaging a member of each set, and means 95 for moving said guides to cause said blades to turn around their longitudinal axes and thereby reverse the direction of propulsion. 100
6. In a screw propeller, the combination 105 with a propeller shaft, of a hub fixed to the latter, two sets of guides in said hub movable in opposite direction relative to each other and longitudinally of said propeller shaft, slides freely movable in said guides transversely to the latter, blades rotatively 110 mounted in said hub and each engaging the slides of two adjoining guides, so that by displacement of the latter the said blades will be turned on their longitudinal axes to reverse the direction of propulsion. 115
7. In a screw propeller, the combination 120 with a propeller shaft, of a hub fixed to the latter, two sets of members guided in said hub and movable in opposite direction relative to each other and longitudinally of said propeller shaft, slides freely movable in said guides and blades revolubly mounted in said hub and each formed with two crank pins adapted to engage the slides of two adjoining guides, so that by displacement of the latter the said blades will be turned on their longitudinal axes to reverse the direction of propulsion. 125
8. The combination with a propeller shaft, 130 of reversible blades thereon and means for reversing the position of said blades, including inter-engaging members movable oppositely relative to each other and longitudinally of said propeller shaft, and adapted to revolve with the latter. 135
9. The combination with a propeller shaft, 140 of reversible blades thereon, and means for reversing said blades, including members movable relative to each other and longitudinally of said propeller shaft and adapted to revolve with the latter and a toggle mechanism for moving said members. 145
10. The combination with a propeller shaft, 150 of reversible blades thereon, members engaging said blades and revolving with said shaft and movable oppositely relative to each other and longitudinally of said shaft, and means for moving said members including a toggle mechanism. 155
11. The combination with a propeller shaft, 160 of a propeller hub, blades reversibly borne in said hub, members guided in said hub and movable oppositely relative to each other and longitudinally of said shaft, slides freely movable in said members and engaged by said blades and means for moving said members and including oppositely swinging yokes engaging said members and a common means for operating said yokes. 165
12. In a propeller shaft, reversible blades 170

thereon, two oppositely movable members engaging said blades and means for moving said members including oppositely swinging yokes, collars carried by said yokes, 5 disks fixed on said shaft and to said members and revolving in said collars and a common means for swinging said yokes.

13. In a reversible propeller, a hollow propeller shaft, a sleeve and rod slidably 10 interposed in each other and movably borne in said hollow shaft, propeller blades, each engaging both said sleeve and rod, two oppositely swinging members connected one to said sleeve and the other to said rod and 15 common means for simultaneously swinging said members in opposite directions.

14. In a screw propeller, the combination with a propeller shaft, of independent members movable longitudinally of and revolving with said shaft, a propeller hub secured 20 to said propeller shaft, propeller blades

borne in said hub and movably engaging said members, so that by the displacement of the latter said blades will be turned on their longitudinal axes to reverse the direction of propulsion. 25

15. In a screw propeller, the combination with a propeller shaft, of interengaging members movable longitudinally of and revolving with said shaft, a propeller hub on 30 said propeller shaft and propeller blades borne in said hub and movably engaging said members so that by the displacement of the latter said blades will be turned on their longitudinal axes to reverse the direction of propulsion. 35

In testimony whereof I affix my signature in presence of two witnesses.

WALTHER GLOOR.
